DESIGN FOR A STUFFED TOY CALF

Mollie J. Denniston, Hills and Dales, near Canton,
Ohio, assignor to Carl C. Steiner, Canton, Ohio

Application March 5, 1945, Serial No. 118,279

Term of patent 14 years

(Cl. D34—2)

To all whom it may concern:

Be it known that I, Mollie J. Denniston, a citizen of the United States, residing at Hills and Dales, in the county of Stark and State of Ohio, have invented a new, original, and ornamental Design for a Stuffed Toy Calf, of which the following is a specification, reference being had to the accompanying drawing, forming part thereof.

Fig. 2 is a front elevation thereof; and
Fig. 3 is a perspective view of the same in a sitting position.

I claim:

The ornamental design for a stuffed toy calf, substantially as shown.

MOLLIE J. DENNISTON.
